ASSIGNORS OF ONE-THIRD TO SAMUEL M. WEST, OF BAXTER SPRINGS, KANSAS.

PNEUMATICALLY-OPERATED PUMP.

1,072,886.

Specification of Letters Patent.

Patented Sept. 9, 1913.

Application filed November 26, 1912. Serial No. 733,618.

To all whom it may concern:

Be it known that we, ERNEST N. WARD and FREDERICK J. WARD, citizens of the United States, and residents of Baxter Springs, in the county of Cherokee and State of Kansas, have made certain new and useful Improvements in Pneumatically-Operated Pumps, of which the following is a specification.

10 Our invention relates to pneumatically operated pumps and more particularly to pumps of a kind suitable for deep wells.

More particularly stated, our invention comprehends a pump of this general character and having improved mechanism for enabling the water discharged from the well to control the admission and discharge of air used for lifting the water.

Reference is made to the accompanying drawing forming a part of this specification, and in which like letters indicate like parts.

Figure 1 is a central section through the mechanism of a pump made in accordance with our invention. Fig. 2 is a fragmentary section on the line 2—2 of Fig. 1 showing a tank forming a part of the apparatus. Fig. 3 is a detail showing the valve mechanism for controlling the air supply.

A well casing is shown at 4 and extends 30 downwardly into the ground 5 so as to constitute in this instance the well proper. It should be understood, however, that our mechanism need not be in the well proper as it can be located in any suitable opening 35 in the ground where a cylindrical casing can be placed so that water will enter it. Located within the casing 4 and concentric to the same is a discharge pipe 6 which is provided with a check valve 7 and with perforations 8. Above the valve 7 and perforations 8 is a packing 9 and below the valve and perforations is another packing 10, these packings being air-tight. A valve 11 is located below the packing 10 and controls 40 the admission of water into the pipe 6. The pipe 6 is provided with a portion 13 located above the well and extending downwardly into a tank 14. This tank is provided with a check valve 15 which is mounted upon a pivot 16 and is used for discharging water from the tank 14. The tank 14 is provided with a guide 17 having the form of a partition of substantially semi-cylindrical form. Within the tank 14 and adjacent to the partition 17 is a float 18 provided centrally with

an opening 19 and extending through this opening is a guide rod 20. This guide rod carries two collars 21—22 each adjustably secured upon it by aid of a set screw 23. The upper end of the guide rod 20 is pivotally connected to a bell crank lever 24, the latter being journaled upon a pin 25 and adapted to rock slightly. Connected with the valve 5 for the purpose of opening the same is a pitman 26. The upper end of this pitman is pivoted to a bell crank lever 27. This bell crank lever is journaled upon a bearing 28 and is provided with an arm 29 carrying a pan 30. This pan is directly below the portion 13 of the pipe 6 through which water is discharged as hereinafter described. A pitman 31 of suitable length is pivotally connected to the upper portion of the bell crank lever 27 and is also connected to a lever 32, the latter being journaled upon a stationary bracket 33. The lever 32 is provided with a number of holes 34 for facilitating the adjustment of the adjacent end of the pitman 31 to different distances from the bracket 33. The bracket 33 is mounted upon a pipe 35 used for discharging air as hereinafter described.

The valve mechanism for controlling the air supply is shown more particularly in Fig. 3. A valve chest is shown at 36 and an air supply pipe at 37. The valve chest 36 is provided with a cylindrical passage 38 and slidably mounted within this passage is a valve piston 39 and two pressure pistons 40 and 41. All of these pistons are carried upon a rod 42. The air supply pipe 37 communicates with the passage 38. An air exhaust pipe is shown at 43 and extends from the passage 38 into the outer atmosphere. The valve chest is provided with a compartment 44, and from the latter two core passages 45 and 46 extend to the ends of the cylindrical passage 38. Two pipe sections 47—48 are connected with a pipe 49 which leads down through the larger pipe 100 and communicates with the interior of the casing 40 as will be understood from Fig. 1. The core passages 45—46 are controllable by gates 50—51, the latter being connected with a T lever 52. A pitman 53 extends from this T lever to the bell crank lever 24. The casing pipe 4 is usually of considerable length and the packings 9—10 are located some distance apart. The air supply pipe 37 is connected with an air 110

compressor or other appropriate source from which air, under pressure is supplied.

The parts being assembled and arranged as above described, we will assume that at a particular moment the tank is empty and that the water in the casing pipe 4 is at its greatest depth, and so its upper edge is at a point just a little below the packing 9. The weight of the float 18 by pulling upon the bell crank lever 24 shifts the pitman 53 to the left, according to Fig. 1, the T lever 52 being rocked slightly in a clockwise position. The gate 51 is now at its uppermost limit of travel, the gate 52 being in its lowermost position. The air from the air supply pipe 37 now passes through the core passage 45 and presses against the adjacent face of the piston 40 so as to force this piston to the left, the other pistons, of course, traveling in the same direction. The air supply pipe 37 is now in open communication with the pipe section 48, whereas the pipe section 47 is closed by the piston 39. Air under pressure now continues through the pipe 49 and escapes into the casing pipe 4 at a point just below the pipe 9. The pressure thus exerted upon the water in the casing pipe 4 forces this water through the perforations 8 and up through the casing pipe 6. The water makes its discharge through the portion 13 of this pipe and in so doing depresses the pan 30, rocks the lever 27 and this rocking movement closes the valve 15 and also pulls the lever 32 so that the pan 32^a carried by it rushes against the adjacent lower end of the pipe 35 and closes the same. The water thus discharged into the tank 14 fills this tank and in so doing raises the float 18. When the float reaches the approximate upper limit of its travel it lifts the collar 21, which rocks the bell crank lever 24. This moves the pitman 53 endwise and causes the T lever 52 to rock in a counter-clockwise direction according to Fig. 1. This shifts the relative positions of the gates 51^a and 52 so that the pistons 39, 40 and 41 travel to the right according to Fig. 1. The air supply pipe 37 is now no longer in communication with the pipe 49, but the pipe 49 is in open communication with the pipe 35. The casing pipe 6 being now empty and the air above the water in this pipe being no longer needed, this air escapes through the pipe 35. In doing this it issues in the form of a strong jet against the pan 32^a and thus causes the lever 32 to swing to the right according to Fig. 1. This movement shifts the pitman 31 and causes the bell crank lever 27 to turn slightly in a clockwise direction according to this figure. The rocking of the bell crank lever 27 raises the pan 30 into proximity to the lower end of the portion 13 of the casing or discharge pipe 15 and also opens the valve 15, the water in the tank 14 now

making its escape and when the float 18 reaches the lower limit of its travel the cycle of operations above described is repeated. The process continues so long as water of proper depth remains in the well or until the supply of air which is cut off by closure of the air supply pipe 37.

We do not limit ourselves to the precise construction shown, as variations may be made therein without departing from the spirit of our invention. Nor do we limit ourselves to the use of any particular materials for purposes of construction, nor to the lifting of water to the exclusion of other liquids, the scope of our invention being commensurate with our claims.

Having now described our invention, what we claim and desire to secure by Letters Patent is:

1. In a pneumatically operated pump, comprising a casing pipe, a discharge pipe mounted within said casing pipe, packings connected with said discharge pipe and said casing pipe and located some distance apart, means for admitting water into said casing pipe, means for admitting water from said casing pipe into said discharge pipe, air mechanism for directing compressed air between said packings for the purpose of forcing a supply of water from between said packings and out through said discharge pipe, a receptacle for receiving said supply of water thus discharged from said discharge pipe, a float mounted in said receptacle and means controllable by the rising of said float for shutting off said air supply.

2. A pneumatically operated pump comprising a discharge pipe for extending down into the well, means for applying air pressure to a liquid in said well in order to discharge said liquid through said discharge pipe, a receptacle for receiving said liquid thus discharged, a pan located within said receptacle and partially within the path of the liquid thus discharged, a valve for automatically preventing egress of water from said receptacle, means controllable by the discharge of water into said receptacle for maintaining said valve closed and mechanism controllable by the discharge of air after the issue of said air for raising the water for opening said valve.

3. A pneumatically operated pump, comprising a casing pipe, a discharge pipe extending into said casing pipe, packings engaging said discharge pipe and said casing, means for admitting water between said packings, means for admitting water from said casing into said discharge pipe, valve mechanism for directing the supply of compressed air between said packings in order to force a supply of water upwardly through said discharge pipe shifting mechanism for actuating said valve mecha-

nism, a float connected with said shifting mechanism, a receptacle for holding a supply of water; said float being located within said receptacle and adapted to be raised as 5 the depth of water within said receptacle increases, and means controllable by movements of said float for actuating said shifting mechanism.

4. A pneumatically operated pump, comprising a discharge pipe, means for applying air pressure to a liquid in a well in order to force said liquid through said discharge pipe, a receptacle for receiving the liquid thus discharged, a float mounted 15 within said receptacle, a guide rod extending through said float and controllable by movement of the latter, a bell crank lever connected with said guide rod, a pitman connected with said bell crank lever, a T 20 lever connected with said pitman and adapted to rock a mechanism connected with said T lever and controllable thereby for turning on and shutting off the supply of air.

5. A pneumatically operated pump comprising a discharge pipe for extending into the well, an air pipe extending through said discharge pipe and communicating with the well outside of said discharge pipe, means for admitting the liquid from the

well into said discharge pipe and for preventing retrogression of said liquid into 30 said well, valve mechanism connected with said air pipe for the purpose of directing air under pressure thereinto, a receptacle for receiving a liquid forced out through 35 said discharge pipe, a float mounted within said receptacle, a mechanism connected with said float and with said valve mechanism for enabling movements of said float to 40 actuate said valve mechanism.

6. A pneumatically operated pump, comprising a discharge pipe for discharging a liquid through a well, a tank for receiving said liquid, a valve for discharging said liquid from said tank, means for applying air under pressure to the liquid in a well for the purpose of forcing the same 45 through said discharge pipe, means for releasing the air after its use for discharging the liquid, a mechanism controllable by the 50 releasing of said air thus used for the purpose of opening said valve.
